The screenshot shows a software interface for managing new hires. The top navigation bar includes 'People', 'Search...', and a user profile for 'Anne Z.' with a dropdown arrow. Below the navigation is a sub-navigation bar with 'Company Directory', 'Org Chart', and 'New Hires'.

The main content area is titled '5 New Hires'. It features two summary sections: 'Onboarding Summary' and 'Checklists Summary'.

Onboarding Summary:

- 1 SETUP NEEDED
- Customize your new hires' onboarding experience.

Checklists Summary:

- 12 TASKS DUE TODAY
- 3 OVERDUE TASKS
- 32 UPCOMING TASKS
- COMPLETED CHECKLISTS

Below these summaries is a section titled 'SORT NEW HIRES' with a dropdown menu set to 'Start Date (Latest first)'. The main area displays five employee profiles in a grid:

Employee	Role	Start Date	Onboarding Status	Checklist Status
XXXX XXXX	Senior Java Developer	STARTING IN 8 DAYS	Employee Onboarding	1 Task Due Today
Bob Roberts	API Engineer	STARTING IN 5 DAYS	Employee Onboarding	4 Tasks Due Today
Sally Johnson	UX Designer	STARTING IN 2 DAYS	Employee Onboarding	12 Tasks Upcoming +12 more
Dave Davis	Senior Java Developer	STARTED OCT. 28	Employee Onboarding	7 Tasks Due Today
Will Williams	API Engineer	STARTED OCT. 21	Employee Onboarding	1 Task Upcoming +10 more

Each row also includes a summary of tasks for the employee:

- Employee 1: 1 Task Due Today, 2 Tasks Upcoming +8 more
- Employee 2: Employee Onboarding, 1 Task Due Today
- Employee 3: Employee Onboarding, 4 Tasks Due Today
- Employee 4: Employee Onboarding, 12 Tasks Upcoming +12 more
- Employee 5: Employee Onboarding, 7 Tasks Due Today

The left sidebar contains a navigation menu with icons and labels: 'Dashboard', 'People', 'Pay', 'Talent', 'Company', 'Admin', 'Demo', and 'Help'.
